VALVE FOR REFRIGERATING APPARATUS

Harry M. Williams, Dayton, Ohio, assignor to
General Motors Corporation, Dayton, Ohio, a
corporation of Delaware

Application December 7, 1934, Serial No. 756,503

1 Claim. (Cl. 251—160)

This invention relates to refrigerating apparatus and more particularly to valve structures.

Heretofore, where a very perfect closing valve is desired, valves or valve seats have often been made of leather, rubber, rubber substitutes or fiber. These materials are, however, subject to considerable wear and distortion, as well as deterioration, particularly when subject to the action of refrigerants in refrigerating systems.

10 It is an object of my invention to provide a valve structure in which one of the sealing surfaces is made of resiliently backed thin metal.

It is a further object of my invention to provide a rubber-like valve seat with a flexible 15 durable metallic surface.

Further objects and advantages of the present invention will be apparent from the following description, reference being had to the accompanying drawing, wherein a preferred form of the present invention is clearly shown.

20 In the drawing:

Fig. 1 shows a diagrammatic representation of a refrigerating system including an enlarged cross sectional view of a thermostatic refrigerant valve embodying my invention; and

25 Fig. 2 shows an enlarged cross sectional view of the valve seat shown in Fig. 1.

Referring to the drawing, there is shown a compressor 20 driven by an electric motor 22 for compressing the refrigerant and for forwarding the compressed refrigerant to a condenser 24 where the compressed refrigerant is liquefied and collected in a receiver 26. The liquid refrigerant is forwarded from the condenser through a supply conduit 28 under the control of an expansion valve 30 to an evaporating means 32 located within a compartment 34 to be cooled. The refrigerant evaporates under reduced pressure within the evaporating means 34 and is returned 30 to the compressor through the return line 36, the return valve 38 and the second return line 40. The operation of the compressor and the electric motor is controlled by a snap acting switch means 42 operated by a bellows connected 40 to the second return conduit 40.

The return valve 38 is provided with a forged body 44 connected by a tubular member 46 to a thermostatic portion 48 which has a tube 50 and a thermostatic bulb 52 connected thereto. Within 50 this thermostatic portion 48 is a bellows 54 which has its movable end wall resting upon a nut 56 mounted on the upper adjustable portion 58 of the valve rod 60. This upper portion 58 is urged in an upward direction by a heavy coil 55 spring 62 extending between the valve body 44

and a spring retainer 64 held by the nut 56. A sealing bellows 66 surrounds the valve stem 60 and is sealed at one end to the valve body and sealed at the other end to the upper adjustable portion 58. The valve stem 60 extends into the 5 valve body and is provided with a valve generally designated by the reference character 70 which is fastened to the valve stem by a nut 72 threaded upon the lower end of the valve stem which holds the valve 70 against a shoulder 74 10 formed on the valve stem. The lower end of the valve stem is provided with a square portion for holding it with a wrench.

Referring more particularly to Fig. 2, the valve is shown formed of a cup shaped metal member 76 containing a rubber or rubber-like composition 78 which fills the cup shaped member excepting for the aperture 80 which receives the threaded portion of the valve stem 60. Permanently secured to the surface of this rubber or rubber-like composition 78 is a thin metal disc 82. This disc may be made of thin copper or bronze stainless steel or other suitable material and may be bonded to the surface of the rubber by vulcanizing, cementing or other suitable means. This metal may be as thin as .005".

This valve structure is adapted to bear against the valve seat 84 within the valve body 74. The valve seat 84 may be formed of the same material as the valve body such as cast brass. This seat is preferably machined to a smooth concentric surface. However, any misalignment in the surface of the seat will be accommodated by the resilient surface provided by the thin metal 82 backed by the rubber or rubber-like composition 78.

This thin metal may be provided with a thin coating of lead so as to provide a soft metal surface for engaging the valve seat. The thin metal, if desired, may be electroplated with brass 40 in order to aid in vulcanizing the thin metal to the rubber-like material. Other metals may be used for the thin metal on the surface of the rubber-like material and valve rubber and other resilient compounds may be used according to their 45 suitability for particular purposes for the resilient backing material 78. The thin metal protects the rubber or rubber-like material from the action of the refrigerants and lubricant in the system and yet this structure retains a substantial portion of the resiliency of the rubber-like material sufficient to insure tight closing of the valve. Although my invention has been shown as applied to a valve proper, it is also equally 50 applicable to the valve seat.

While the form of embodiment of the invention as herein described constitutes a preferred form, it is to be understood that other forms might be adopted, all coming within the scope of the claim which follows.

5 What is claimed is as follows:

A valve member including a cup-shaped member, a rubber-like material within and substantially filling the cup-shaped member, and a flat

disc-shaped member providing a seating surface of thin metal less than 0.006" thick extending across the face of the rubber-like material within the cup-shaped member and extending substantially into contact with the inner wall of 5 the cup-shaped member, said thin metal being bonded to the rubber-like material.

HARRY M. WILLIAMS.
